CLAIM

The ornamental design for a combined wireless audio transmitter and plural receivers, as shown and described.

DESCRIPTION

FIG. 1 is a top, front and right-side perspective view of a combined wireless audio transmitter and plural receivers embodying our new design;

FIG. 2 is a bottom, rear and left-side perspective view thereof;

FIG. 3 is a top plan view thereof;

FIG. 4 is a bottom plan view thereof;

FIG. 5 is a front view thereof;

FIG. 6 is a rear view thereof; and,

FIG. 7 is a left-side elevational view thereof; the right-side elevational view being a mirror image.

The broken lines in the drawings depict parts of the combined wireless audio transmitter and plural receivers that form no part of the claimed design.
